GEORGE MIKULA, OF JERSEY CITY, NEW JERSEY

FLOATING AND CUSHIONING DEVICE FOR AEROPLANES

Application filed July 25, 1928. Serial No. 295,261.

This invention relates to improvements in aeroplanes and has specific reference to attachments for land planes whereby in the event of shortage of fuel when over a stretch of water a plane may drop onto and be supported by said water and be sustained thereon for an indefinite period of time to await a rescue or for awaiting a fresh supply of fuel, after which the sustaining elements may be folded within suitably provided pockets when the plane may proceed on its initial course. But to permit of this, the wing attachments must first be entirely collapsed into their pockets, the attachments of the fuselage being collapsed later after the plane rises from the water to proceed on its flight.

Briefly the invention contemplates providing a land plane with devices normally folded within the lines of the plane structure which may be quickly inflated with compressed air to simulate in buoyant efficiency a hydroplane, sea-plane or the like.

In reducing my invention to practice I preferably provide shallow pockets in the undersides of the fuselage and the outer, under portions of the wings, wherein are received tightly folded bags of flexible rubberized fabric requiring little space when folded in bellows formation. Devices being provided and controlled by levers or the like at the control of the pilot for forcing air under pressure into the said bags after devices are operated to release suitable catches which lock the bag frames in normal collapsed folded condition.

The invention also provides means for inflating the air bags in the event the plane engine should "go dead" said means comprising an auxiliary pump operated by electrical current and a controlling switch for said pump being controlled by a lever at the pilot's seat.

In the drawings:

Fig. 1 is a diagrammatic perspective view of my improved convertible aeroplane shown in flight and about to land on a body of water, parts being omitted.

Fig. 2 is a diagrammatic longitudinal sectional elevation showing the bags or floats collapsed or folded within their respective

pockets or housings and with other parts omitted.

Fig. 3 is an enlarged diagrammatic side elevation of the aeroplane engine, an air pressure pump and controlling connections, 55

Fig. 4 is a greatly enlarged longitudinal sectional elevation, and somewhat diagrammatic, showing more clearly an auxiliary air pressure pump employed, parts being omitted and the lower bag being released and unfolded ready for inflation, 60

Fig. 4^a is a detail sectional view of a valve for controlling the air in the wing floats or bags, 65

Fig. 5 is a diagrammatic elevation showing the position of the pump valve when the floats, or bags, are being filled with compressed air, 65

Fig. 6 is a similar diagrammatic elevation but showing the pump valve in the position when the floats or bags are being emptied or collapsed, 70

Fig. 7 is a detail section showing the pump valve in the closed position, 75

Referring to the drawings in detail, the fuselage of the convertible aeroplane is shown at 10, the wing at 11, the engine at 12, the propeller at 13, the landing gear at 14, the passenger entrance at 15, the pilot's window at 16, and the rudder and tail group at 17. 80

In carrying out my invention I provide a recess 18 in the bottom of the fuselage 10, extending longitudinally thereof, in which I place a casing or housing 19, provided with a marginal flange 20, against which a cover 21, may be locked by spring pulled catches 22, hinged to said housing 19 as at 23. 85

The pilot's seat (not shown) will be positioned at about the letter P so that he may have access to the several control levers to be hereinafter described.

Near the tail group 17 of the fuselage 10, I provide a smaller pocket 24, containing a flanged housing 25 and a cover 26 normally locked in closed position by spring pulled catches 27 similar to the catches 22, just described. 95

To provide against accident caused by tilting or violent rocking of the aeroplane when resting on rough water, I preferably

provide pockets 28, in the underside of the wings, to receive housings or casings 29 flanged at 30, against which covers 31, are normally locked by spring pulled catches 32, 5 and normally folded into the housings 19, 25 and 29, are flexible bags 33, 34 and 25 respectively.

The flexible bags 33, 34 and 25 are preferably of layer canvas permeated with rubber 10 and pre-pressed to form bellows folds 36, so that when the air is pumped out and a vacuum created they will be drawn into their respective housings and will fold compactly without manual attention, and the covers of 15 the housings will be snapped in under their respective catches in closed positions.

Should it become imperative, in case of fuel shortage or for other reasons, to alight on a body of water, the pilot pushes forward 20 on a lever 37, pivoted at 38, and having a fork 39 at its lower end to engage in revolute relation, a grooved clutch sleeve 40, which is slidable on, but rotative with the engine shaft 41, of the plane, see Fig. 3 of 25 the drawings.

The forward movement of the handle of the lever 37, through suitable wires 42, passing over rollers 43, serves to disengage all of the catches 22, 27 and 32 to which said wires 30 are connected and permit the bags 33, 34 and 35 to unfold out of their respective housings and in the same movement of the lever 37, it moves the sleeve clutch part 40, into interlocking engagement with a companion clutch 35 member 44 on the shaft 45, of the rotor 46, of an air pump 47, having out and incoming pipes 48 connected to a shiftable valve 49 also connected with a short inwardly directed nipple 50 and at the opposite side to an air 40 pipe line 51, hereinafter described.

The valve 49 may be adjusted by a bell-crank lever 52, connected at one end by a link 53, to a short arm 54 keyed to a shaft 45 extending outwardly through the valve casting as shown in Figs. 2, 3 and 4 of the drawings.

The free end of the bell-crank lever 52 terminates in a handle 55, carrying a hand operated bolt 56, adapted to enter one of three 50 notches 57, in a segmental arm 58, formed at the top of a bracket 59, to which the bell-crank 52 is pivoted.

To properly control the compressed air when inflating and deflating the bags or 55 floats 33, 34 and 35, I provide the valve 49 with two curved passages 60 constituting in effect a four part valve so that it may be employed when inflating the bags and also when deflating the same as will now be described.

60 When it is desired to alight on a body of water the lever 37 is pushed forward (as above stated) to release the air bags 33, 34, and 35, and to connect clutch parts 40—44 to start the pump 47, but prior to this the valve 65 49, must be turned from the normally closed

position (Fig. 7) to the open compression position (Fig. 5) and when the bags are blown up to their capacity the lever 52 is operated by its handle 55, to bring the valve back to the closed position of Fig. 7, thus locking the air line against exhaustion.

Safety valves such as those shown at 62, 63, 64, may be employed to control the pressure in the bags.

When it is desired to rise from the water, it is necessary to deflate the wing bags first as they would retard the plane and would also reduce the lifting power of said wings, and to accomplish this, I employ a three way valve 65, placed in the air line 51, forward of the junction of the branch pipe 66 to the bag 33.

The construction and operation of this valve 65, is clearly shown in Figs. 4 and 4^a of the drawings and may be described as follows:

Just prior to operating the bell crank lever 52 to turn the valve 49 into the exhausting or deflating position shown in Fig. 6, a lever 67 is operated to draw the valve lever 68 through a wire 99, to the dotted position 68^a in Fig. 4, and the full line position of Fig. 4^a, and it is held in that position against the action of a pull spring 69, until the wing bags are deflated, after which the lever 67 is released and the said spring acts to rotate the valve 65, back to its normal position to establish the air line from the bags 33 and 34 which are then deflated by the continuing action of the pump 47 as the plane rises into the air.

In the event the plane engine should "go dead" and its power was not available for driving the pump 47, I may employ an electric motor 70 which may be connected to the pump direct as shown in Figs. 2 and 3, or an electric pump 71 connected by a pipe 72, to the air line 51, may be employed. A lever 73 connected by a wire or cord 74 may be connected to an electric switch 75 to control said pump.

What I claim as new, is:

1. In an aeroplane, embodying the usual fuselage, motive means and wings; pockets arranged in the undersides of said fuselage and said wings; collapsible and expansible bags normally held in said pockets; releasing means for said bags; a pivoted lever adjacent to the pilot's seat; connecting means between said releasing means and said lever whereby said bags may be released by the operation of said lever; an air pump having pipe connections to said bags whereby to inflate said bags when desired, and a clutch mechanism on a shaft of said motive means and said pump connected to said lever whereby the operation of said lever in the releasing of said bags will connect said motive means to said air pump.
2. In an aeroplane, embodying the usual

fuselage, motive means and wings, pockets arranged in the undersides on said fuselage and said wings; collapsible and expansible bags normally held in said pockets; releasing 5 means for said bags; a pivoted lever adjacent to the pilot's seat; connecting means between said releasing means and said lever whereby said bags may be released by the operation of said lever; an air pump having 10 pipe connections to said bags whereby to inflate said bags when desired, a clutch mechanism on a shaft of said motive means and said pump connected to said lever, whereby the operation of said lever in the releasing 15 of said bags will connect said motive means to said air pump, and a reversing valve in connection with said air pump whereby said air pump may operate to draw air from the atmosphere and compress it into said bags, or 20 vice versa.

3. In an aeroplane as set forth in claim 2, a second valve whereby the bags in the wings may be separately connected to said air pump, the rest of the bags being then shut 25 off therefrom, or vice versa.

4. In an aeroplane having mechanical motive means therein, including a shaft; a central operating element adjacent to the pilot's seat; inflatable devices on said aeroplane 30 normally being in a collapsed position; means to release said inflatable devices; connections between said means and said central operating element; an air pump with pipe lines to said inflatable devices; a clutch 35 on said motive shaft adapted to connect the shaft of air pump to said motive shaft or to disconnect it from the same, said clutch being also connected to said central operating element so that when releasing said inflatable 40 devices said element will automatically connect said two shafts.

5. In an aeroplane floating mechanism as set forth in claim 4, a reversing valve in connection with said air pump whereby said air 45 pump may draw air from the atmosphere and compress it into said inflatable devices, or vice versa.

6. In a floating mechanism for aeroplanes as set forth in claim 4 a selective valve whereby a selected group of said inflatable devices 50 may be connected to said air pump and the rest of said devices shut off therefrom.

Signed at New York, in the county of New York and State of New York, this 9th day 55 of July, A. D. 1928.

GEORGE MIKULA.
